UNITED STATES PATENT OFFICE.

RALPH S. PEIRCE, OF CHICAGO, ILLINOIS.

APPARATUS FOR ERECTING AERIAL CABLES.

No. 840,009.

Specification of Letters Patent.

Patented Jan. 1, 1907.

Application filed February 27, 1905. Serial No. 247,491.

To all whom it may concern:

Be it known that I, RALPH S. PEIRCE, a citizen of the United States of America, and a resident of Chicago, county of Cook, and 5 State of Illinois, have invented a new and useful Improvement in Apparatus for Erecting Aerial Cables, of which the following is a specification.

My invention pertains to an improved 10 method and apparatus for the erection of lead-covered aerial cables.

It is customary in erecting cables to first 15 string the messenger-wire or supporting-strand along the line of poles or other supports that is to bear the length of the cable to be erected and then by means of a running rope previously strung parallel with the messenger-wire to pull the cable up and along the messenger-wire, supporting it by 20 suitable hangers placed on the cable as it unrolls from the reel. Under some methods the cable-hangers are hooked over the messenger-wire as it passes from the reel, and under others some of the hangers are not attached to the messenger-wire until after the 25 cable is pulled over the entire length of the run. In the latter event some form of roller is usually applied to the pole just beneath the messenger-wire support and the cable 30 passes over this roller during the process of drawing it into position, a man being stationed at each pole to assist the few hooks over the messenger-wire support as they pass until the last span is about to be pulled, when 35 a signal is given, after which all men attach all hooks to the messenger-wire as the various portions of the cable are then entering their respective spans.

Where all of the cable-hangers are applied 40 to the messenger-wire during the drawing of the cable into position, it is customary either to provide a special messenger-wire support over which the hooks of the hangers may slide freely during the drawing of the cable 45 or to use an ordinary form of messenger-wire support and to station a man at each pole to lift the hooks over the messenger-wire support as they pass. Devices have been produced with a view to removing the necessity for a man at each pole; but such devices have been limited to use in the erection 50 of cable with a special type of hanger or to the erection of cable with a hanger conforming to some limiting detail in design 55 forced by the man-displacing device.

It is the object of my invention to make

possible the erection of aerial cables using any type of hanger desired without the necessity of employing men upon the poles during the drawing of the cable, and, further, to insure against the possible falling of the cable during the process of erection by the accidental slipping of the messenger-wire from its temporary point of support, or of the hook from the messenger-wire, which events sometimes occur in present practice, allowing a considerable length of cable to drop to the ground. I accomplish this object by the use of a device which is shown in the accompanying sheet of drawings, in which—

Figure 1 is a view of the device as applied to the pole ready for use. Fig. 2 is a side view of the pole with one form of messenger-wire support in common use at the time of my invention. Fig. 3 is a side view in section of the device embodying my invention. Fig. 4 is a side view, partly in section, of a pole top with my device in place ready for use. Fig. 5 is a front view of my device, partly in section. Fig. 6 is a front view, 80 partly in section, of a modified form.

In the drawings the numeral 1 signifies an ordinary telephone or telegraph pole to be used in supporting a section of aerial cable. To this pole is secured by lag-screw 2 a messenger-wire support 3, which consists in the case shown of a cast-iron block 3' and a wrought-iron clamping-plate 3'', which serve to hold the messenger-wire in place in the block 3' under pressure of the bolt 2, which 85 clamps the whole structure firmly together. 90

My invention may be applied to any style or modification of messenger-wire supports, these supports forming no portion of my invention.

The device which I use to facilitate the erecting of the cable may be called a "cable-shoe" or "cable-runway" and is referred to on the drawings by the numeral 4. It consists in its preferred form of a plate of sheet-steel curved in such a manner that in its vertical and longitudinal cross-section it presents the form of an open hook, as shown clearly in Figs. 3 and 4. The shank or portion of this hook by which it is secured to the 100 pole is curved to conform with the circumference of the pole, so that when applied to the pole there will be a considerable amount of bearing-surface between it and the surface of the pole. The hook portion of the device is 105 curved, as shown in Fig. 5, so as to allow the cable and messenger-wire to lie freely within 110

it and be supported by it, as most clearly shown in Figs. 1 and 4. The lateral edges of this portion of the device are curved downwardly, so that as the cable is being drawn along, while supported within the hook, it or the hangers on it will not be caught by the edges. For this reason also the supporting-surface of the hook is made very smooth and is polished.

10 In the shank of the hook there is a hole 4' of general rectangular shape which has at its upper side an extension 4" of about the diameter to enable it to properly conform to the size of the lag-bolt 2. The hole 4 is of 15 such size as to allow the messenger-wire support 3 to pass through it as a whole. If while the messenger-wire support 3 is fastened to the pole, but before the bolt 2 has been driven entirely home, the cable shoe or 20 runway be slipped over the messenger-wire support 3 until the shank of the hook assumes a position behind it, the shoe or runway may be pressed down, so that the extension 4" of the hole 4' engages the lag-bolt. After 25 this the lag-bolt may be tightened up and the whole device clamped in place securely, assuming the position most clearly shown in Fig. 4. In putting my invention into practice one of these devices is clamped onto each 30 of the poles in the run over which the cable is to be drawn. The messenger-wire 5 is merely laid in the hook portion of the shoe, being firmly anchored at each end. The cable-reel is then brought to a point near one end of the 35 messenger-wire, and one end of the cable having been secured to a running rope previously laid in the hook portions of the shoes beside the messenger-wire the cable is pulled along over the run by means of any available 40 power. As the cable is unreeled hangers are applied to it at frequent intervals, these being clamped over both the cable and the messenger-wire.

45 In the drawings, at 7 in Fig. 4, is shown an improved marline-hanger devised by me covered by my patent application, Serial No. 247,489, filed February 27, 1905, in which a permanently-closed loop embraces both cable and messenger-wire. This form of hanger is 50 shown as a preferred form of hanger; but it is not essential to the present invention that this form of hanger be used.

55 The cable that is being erected is shown at 6 in the drawings, and the hangers at 7. As the cable and hangers progress along the messenger-wire the hangers slide over the messenger-wire, being pulled along by the cable. At each pole the curved portion of my shoe or runway serves to raise the cable 60 on a level with the messenger-wire 5, as best shown in Fig. 4, the curved surface of the shoe preventing the hangers from catching or from meeting with undue friction. Each hanger as it passes the supporting device 65 forces the messenger-wire 5 up to a slight

degree, so as to allow a portion of the hanger to pass between the messenger-wire and the supporting device. By this method any convenient length of cable may be erected without employing men on the poles during 70 the pulling of the cable. After the cable has been pulled into place throughout its entire length it may be supported temporarily at each pole by a suitable lashing of rope to the upper portion of the pole and the shoe or 75 runway removed, after which the messenger-wire is secured in its proper place on the permanent messenger-wire support 3, the temporary lashing then being removed. It is possible, however, by providing a slot in the 80 side of the shank of the hook to remove the hook without resorting to the temporary lashing, the slot serving to permit the withdrawal of the hook from the lag-bolt 2 by 85 lifting it slightly and moving it sidewise, so that the slot 8 permits its passage from the lag-bolt, messenger-wire, and cable after the messenger-wire with its attached cable has been placed in position in the clamp 3. A hook having a slot 8 for this purpose is shown 90 in Fig. 6. After this is done the lag-bolt 2 may be tightened in the usual manner and the cable left permanently supported.

I do not wish to limit myself in all respects to the exact construction here shown and described. It is obvious that for other forms of standard messenger-wire clamps than the one here shown the shape of the opening in the shank of the shoe or runway might in some cases be modified to conform to the shape of the messenger-wire clamp. I prefer to provide against undue friction between the cable and the shoe or runway by merely curving and polishing the surface over which the cable slides; but any other well-known friction-reducing means might be employed. Obviously, also, other changes might be made in the form of the shoe or runway or in the material from which it is made without departing from the spirit of my invention.

110 What I claim as new, and desire to secure by United States Letters Patent, is—

115 1. In a device for supporting aerial cables during the process of erection, a plate having a curved surface for engaging the supporting-pole, said plate having an opening by which it may be placed upon the pole over and surrounding a messenger-wire support and having a recess in the upper edge of said opening of such dimension as to receive the shank of the lag-screw sustaining the messenger-wire support and adapted to be retained upon the lag-screw by engagement with its sustained messenger-wire support, a hook portion integral with said plate upon which the cable 120 may rest, and friction-reducing means associated with said hook portion of said plate over which the cable may be drawn without abrasion, substantially as described.

125 2. In a device for supporting aerial cables 130

during the process of erection, a plate having a member curved to embrace the supporting-pole, a hole in said member for passing over a messenger-wire clamp supported on said pole, 5 a slot extending from said hole for embracing a bolt, securing said messenger-wire clamp to said pole, and a curved hook member having a smooth surface through which said cable may be drawn without abrasion, substantially as described.

3. In combination with a pole for supporting electrical wires, a messenger-clamp, a bolt for securing said clamp to said pole, a cable-runway for temporarily supporting a 15 cable, a perforated shank for said runway, curved to conform to the surface of said pole, and adapted to be held in place by said messenger-wire clamp, and a curved hook member for said runway having a smooth surface

through which said cable may be drawn without abrasion, substantially as described. 20

4. In a device for supporting aerial cables during the process of erection, a plate having a curved portion for engaging directly the supporting-pole, a hole in said curved portion for passing over the shank of a bolt projecting from said pole, and a curved hook member having a smooth surface through which said cable may be drawn without abrasion, substantially as described. 25

Signed by me at Chicago, county of Cook, State of Illinois, in the presence of two witnesses. 30
